United States Patent Office.

GEORGE W. YOUNT, P. P. REISTER, A. L. KEEPORTS, AND WILLIAM YOUNT,
OF LITTLESTOWN, PENNSYLVANIA.

Letters Patent No. 99,271, dated January 25, 1870.

IMPROVED CURTAIN-HOLDER.

The Schedule referred to in these Letters Patent and making part of the same.

To all whom it may concern:

Be it known that we, GEORGE W. YOUNT, P. P. REISTER, A. L. KEEPORTS, and WILLIAM YOUNT, of Littlestown, in the county of Adams, and in the State of Pennsylvania, have invented a certain new and useful Improvement in Curtain-Holders; and do hereby declare that the following is a full, clear, and exact description thereof, reference being had to the accompanying drawing, making a part of this specification, in which—

Figure 1 is an edge view of a curtain, with our improved holder attached;

Figure 2 is a front elevation of the same; and

Figure 3 is a bottom view of the holder.

Letters of like name and kind refer to like parts in each of the figures.

Our invention has for its object the securing of curtains at any desired height; and to this end,

It consists in the peculiar construction of the holder or clasp, and in its application to a curtain, substantially as shown, and for the purpose specified.

In the annexed drawings—

A represents the holder, formed of round wire, which, at its centre lengthwise, B, is bent in a spiral form, with two or more coils, from whence each half curves outward and upward, to a certain point, C, and from thence inward and upward, past the centre, transversely, and again inward until they meet at the vertical centre D, where they terminate in short, vertically-parallel pieces E, which are caused to impinge firmly against each other by the outward spring of the spiral B.

As thus constructed, it will be observed that an elliptic space, having a sufficient size to receive the bottom roll of a curtain, is left between the upper half of the bows, so that if said bows are spread apart, by pressing together the lower parts of the holder, passed over said roll F, and permitted to close upon the curtain G, the holder will be firmly attached to and maintain its position upon the latter, and at the same time prevent the unrolling of the roll.

In order to lower the curtain, it is only necessary to pull downward upon the holder; but when it is desired to raise said curtain, said holder must be loosened, so

as to permit it to be carried with the curtain as it is rolled upward.

It being desirable that the ends of the bows E should have a large bearing-surface upon the curtain, the wire at D is bent outward and over, so as to nearly form a small circle, and is then extended downward beside the upper half of the bow, and secured to the same at C, by which means the above-named result is obtained, and, at the same time, the bows strengthened.

Another advantage arises from forming the upper half of the bows of two wires, as, by passing each inner wire between those forming the opposite bow, the lateral adjustment of said bows is at all times maintained.

This device obviates the necessity of employing any of the expensive curtain-fixtures which are so easily deranged, and in their stead furnishes a cheap, convenient, and durable means for retaining a curtain at any desired height.

It is also applicable to rolls of paper, oil-cloth, or any goods put up in a similar manner, which it may be desired to exhibit partially unrolled.

Having thus fully set forth the nature and merits of our invention,

What we claim as new, and desire to secure by Letters Patent, is—

As a new article of manufacture, the within-described curtain-holder, consisting of the double-curved bows B, C, and D, connected together at their lower ends by means of a spiral coil, and made double and interlocking at or above their vertical centres, substantially as and for the purpose shown.

In testimony that we claim the foregoing, we have hereunto set our hands, this 7th day of December, 1869.

GEO. W. YOUNT.
P. P. REISTER.
A. L. KEEPORTS.
WILLIAM YOUNT.
